UNITED STATES PATENT OFFICE.

NICOLAS BASILE COSTOVICI, OF LAUSANNE, SWITZERLAND.

DEVICE FOR QUICKLY TRACING CIRCLES OF GIVEN DIAMETERS.

1,341,457.

Specification of Letters Patent.

Patented May 25, 1920.

Application filed October 27, 1917. Serial No. 198,747.

To all whom it may concern:

Be it known that I, NICOLAS BASILE COSTOVICI, a subject of the King of Rumania, and residing at Lausanne, Switzerland, have invented a certain new and useful Improved Device for Quickly Tracing Circles of Given Diameters, of which the following is a specification.

The object of my present invention is a device for quickly tracing circles of a given diameter. Said device comprises a ruler provided with perforations whereof one serves as a guide for a center point which is passed through the ruler into a suitable drawing surface and another as a guide for a drawing pencil or pen in such a manner that by swinging the ruler around the center point a circle of a given diameter may be traced on the drawing surface by means of said drawing pencil or pen. My device is further provided with a holding bar for the center point whereby the latter is held from the outside of the largest possible circle to be drawn with the device in such a way, that no hole will be made by the point in the drawing surface.

The drawing represents one embodiment of my invention.

Figure 1 is partly a section, partly a side elevation of the device in its working position.

Fig. 2 is a side elevation of the ruler incased within the holder.

Fig. 3 is a section on line III—III in Fig. 1.

Fig. 4 is a section on line IV—IV in Fig. 1.

Fig. 5 is a section on line V—V of Fig. 2 and

Fig. 6 is an end view of the ruler as seen from the left in Fig. 1.

A flat ruler 2 marked on one of its side edges with a scale and preferably made of transparent material, such as celluloid is provided on its longitudinal center line with a number of perforations 2' at a certain distance apart, and with a slot 5 cut near the one end of it on the said center line. Above this slot 5 there is provided a slide piece 4

made adjustable along a small scale 4' by means of a micrometric screw 3 the free face end of which is marked with a scale providing for a fine adjustment of the slide as indicated by the hand 4" fixed to the slide.

The slide has a fine hole 4'', for receiving a needle 1 serving as center point when trac-

ing circles with the device. In the working position of the device (Fig. 1) this center point is adjustably held at its upper end within a perforation of a sleeve 6 by means of a set screw 7. The sleeve 6 is fitted with a laterally projecting ear 8 wherewith it is held between the side walls of a flat hollow bar 9 of U shaped cross section. This bar 9, open along its whole bottom side, is extended in width at its opposite end with regard to the sleeve 6 and is of a greater length than the ruler 2 so that the latter may be incased within it as shown in Fig. 2, that is to say, the bar 9 serves as casing for the ruler when not in use. Besides, owing to this greater length of bar 9, it is possible to hold the center point from the outside of the greatest possible circle to be drawn with the device without any perceptible downward pressure, so that no hole will be produced on the drawing surface however many concentric circles may be drawn thereon. In order to prevent any hole from being made in said surface it is advisable to give a strongly conical shape to the said center point.

The use of said device is as follows:

The center point clamped fast within sleeve 6 is passed as described above into the hole 4''' of slide piece 4 while the ruler 2 is laid on the drawing surface and the bar 9, held with one hand, is set with its downwardly extended edge on the said drawing surface. With the other hand a drawing instrument such as a pencil or a pen is inserted into one of the holes 2' with its point bearing against the drawing surface. By swinging by means of the drawing instrument the ruler around the center point a circle will be traced on the drawing surface of a diameter corresponding to the distance between center-point and pencil. By inserting the latter into another hole 2' or by moving the slide 4 by means of the micrometric screw another circle, concentric with the first, may be drawn, when swinging the ruler around the center point. In such a manner as many concentric circles as desired may be drawn.

With the device as represented in the drawing circles of a given diameter may be drawn at once without first measuring on a scale so that compasses, ruler and scale are combined into one instrument. By using compasses errors are easily made when measuring the diameters of circles. This is

hardly possible with the device as described and shown, as the corresponding diameters are marked in numbers beside each hole 2'.

The instrument may be built up of any suitable transparent or non-transparent material, such as of celluloid, metal, wood or the like.

I claim—

10 A device for tracing circles of a given diameter comprising a ruler bearing a scale on one of its side edges and having holes along its longitudinal center-line for the insertion of a drawing instrument, a center point adapted to enter one of said holes, and

a bar of greater length than the said ruler 15 and having a downwardly extended edge adapted to rest on a drawing surface and also a freely projecting end, a sleeve adjustable therein forming a support for said center point, the said bar being shaped so as to receive the said ruler when not in use.

In testimony whereof I affix my signature in the presence of two witnesses.

NICOLAS BASILE COSTOVICI.
